UNITED STATES PATENT OFFICE.

JOHN ZIMMERMAN, OF COUNCIL BLUFFS, IOWA.

BAFFLE-PLATE DOOR.

1,104,950.

Specification of Letters Patent. Patented July 28, 1914.

Application filed January 26, 1914. Serial No. 814,302.

To all whom it may concern:

Be it known that I, JOHN ZIMMERMAN, a citizen of the United States, residing at Council Bluffs, in the county of Pottawattamie and State of Iowa, have invented certain new and useful Improvements in Baffle-Plate Doors, and have described the same in the following specification, illustrated by the accompanying drawings.

10 My invention relates to that class of baffle-plate doors which are used in connection with the fireboxes of locomotives.

15 The main objects of the invention are to improve the firing, and to regulate the fire, in such fireboxes; to economize fuel; to maintain a uniform temperature; and to protect the fireman from the heat. To accomplish these objects I incorporate in my improved baffle-plate door, a door proper covering a portion of the doorway, and a baffle-plate, slidably attached to the door proper, and extending through the doorway.

20 In the accompanying drawings, illustrating the best manner in which I have contemplated applying the principles of the invention, Figure 1 is front elevation of a firebox provided with a baffle-plate door which is constructed in accordance with these principles. Fig. 2 is a vertical section on the section line of Fig. 1, but showing the baffle-plate in a different position of adjustment. Fig. 3 is a side elevation of the door in a modified form.

25 In the illustrative specimen of my invention shown in Figs. 1 and 2, the door proper is a rectangular iron plate 1, which is attached to the front plate 2 of the firebox 6 by the hinge 3 and the latch 4 in a well known manner. This closes the upper portion, approximately half, of the rectangular doorway 5 opening through the plate 2 into the firebox. The baffle-plate 7 comprises a single rectangular metallic plate, bent into two rectangular portions, namely: the vertical portion 8 and the approximately horizontal portion 9. The portion 8 has two vertical spaced slots 10 and is adjustably attached to the door proper by the two sleeved bolts 11, working in those slots respectively as the baffle-plate is raised and lowered. Operatively the lower part of the doorway is covered, as in Fig. 1, by sliding the baffle-plate to its limit downward on the sleeve-bolts, or is wholly uncovered by 30 sliding that plate to its limit upward, and is either opened or closed partially by

sliding the same to an intermediate position, as shown in Fig. 2. By raising or lowering the baffle-plate, the fireman increases or diminishes at will the horizontal current of air which is thereby and thereunder directed over the coals; and by turning the nuts 12 on the sleeve-bolts he secures the baffle-plate immovably in any higher or lower position of adjustment which may be 35 desired. In every position this plate is protected by the downward current of air between itself and the door proper, and is thereby prevented from burning out.

40 In that modification of my invention which is shown in Fig. 3, the door 1' is fastened at the top to the plate 2 by horizontally alining hinges 3', and is provided with an arm 13 carrying a weight 14 by which the door 1' is either held in the closed position shown in full lines in that figure, or held alternatively in the raised position shown in dotted lines, as convenience may require. By a lug 15, projecting from the arm 13, and an abutting screw 16, seated adjustably 45 in the plate 2 and working through a hold in the door 1', the latter may be stopped in an intermediate position partly open, when desired.

45 Constructed as described, my improved baffle-plate door presents a number of advantages which are not fully particularized among the above stated objects of the invention. Completeness of combustion and consequent saving of fuel are promoted by the 50 admission of an air current in regulated quantities under the door proper, and by directing that current over, near and against the coals. Ordinary firing is effected without swinging the door open, and without 55 thereby cooling the firebox, the coal being thrown in under the baffle-plate. Uniform temperature and uniform steam pressure are promoted by feeding the fire little at a time as needed. The condition and color of the 60 fire can be watched continually from end to end of the firebox without opening the door; and holes in the fire bed promptly and easily detected and mended. Firing can be done 65 deliberately under the baffle-plate, and the coal can be placed conveniently here and there, where needed. By the maintenance of an even temperature in the firebox, sudden and destructive contractions and expansions 70 of the boiler sheets are prevented. By the vertical member of the baffle-plate, the fireman is ordinarily protected from blistering 75

heat; and by the raising and lowering of that plate, the fire is controlled in different parts of the firebox.

I claim as my invention—

- 5 1. A baffle-plate door of the specified class, comprising a swinging door adapted to close the upper portion of the doorway, and an adjustable baffle-plate carried by the swinging door and having two angularly disposed portions, one of those portions being disposed vertically and spaced from the outside of the swinging door, and the other of those portions being disposed horizontally and extending through the under portion of the doorway.
- 10 2. A baffle-plate door of the specified class, comprising a swinging door for the upper portion of the doorway, and a slidably bent baffle-plate carried by the swinging door; the upper portion of the baffle-plate being uniformly spaced from the swinging door, and
- 15
- 20

the lower portion of the baffle-plate being adjustably spaced below that door.

3. A baffle-plate door of the specified class, comprising a swinging door, means for holding the same in different positions of adjustment, a slidably bent baffle-plate carried by the swinging door, and means for holding the baffle-plate in different positions of adjustment relative to the swinging door; the upper portion of the baffle-plate being spaced at a predetermined distance from the outside of the swinging door, and the lower portion of the baffle-plate being adjustably spaced from the bottom of the swinging door.

In testimony whereof I subscribe my name hereto in the presence of two witnesses.

JOHN ZIMMERMAN.
